(57) **CLAIM**

The ornamental design for a mobile phone, as shown and described.

DESCRIPTION

FIG. 1 is a front right perspective view of a first embodiment of a mobile phone showing our new design.

FIG. 2 is a rear right perspective view of the mobile phone of FIG. 1.

FIG. 3 is a rear left perspective view of the mobile phone of FIG. 1.

FIG. 4 is a front view of the mobile phone of FIG. 1.

FIG. 5 is a rear view of the mobile phone of FIG. 1.

FIG. 6 is a left side view of the mobile phone of FIG. 1.

FIG. 7 is a right side view of the mobile phone of FIG. 1.

FIG. 8 is a top view of the mobile phone of FIG. 1.

FIG. 9 is a bottom view of the mobile phone of FIG. 1.

FIG. 10 is a front right perspective view of a second embodiment of a mobile phone showing our new design.

FIG. 11 is a rear right perspective view of the mobile phone of FIG. 10.

FIG. 12 is a rear left perspective view of the mobile phone of FIG. 10.

FIG. 13 is a front view of the mobile phone of FIG. 10.

FIG. 14 is a rear view of the mobile phone of FIG. 10.

FIG. 15 is a left side view of the mobile phone of FIG. 10.

FIG. 16 is a right side view of the mobile phone of FIG. 10.

FIG. 17 is a top view of the mobile phone of FIG. 10.

(Continued)

FIG. 18 is a bottom view of the mobile phone of FIG. 10. FIG. 19 is a front right perspective view of a third embodiment of the mobile phone showing our new design. FIG. 20 is a rear right perspective view of the mobile phone of FIG. 19. FIG. 21 is a rear left perspective view of the mobile phone of FIG. 19. FIG. 22 is a front view of the mobile phone of FIG. 19. FIG. 23 is a rear view of the mobile phone of FIG. 19. FIG. 24 is a left side view of the mobile phone of FIG. 19. FIG. 25 is a right side view of the mobile phone of FIG. 19. FIG. 26 is a top view of the mobile phone of FIG. 19; and, FIG. 27 is a bottom view of the mobile phone of FIG. 19.
